UNITED STATES PATENT OFFICE.

AUNCEL BRIAN FEE HERN AND ALBERT HENRY FEE HERN, OF LONDON, ENGLAND.

LIFTING JACK.

Application filed June 13, 1927, Serial No. 198,653, and in Great Britain December 2, 1925.

This invention relates to lifting devices spaced apart an equal amount and the links or jacks of the type comprising a plurality 7 and 7^a crossed. of toggles adapted to be operated by nut and screw mechanism and the object of the invention is to provide an improved jack of this class which is of simplified construction and capable of relatively considerable expansion or contraction.

The lifting device or jack according to the invention comprises a base portion and a crutch portion connected to each other at each side by pairs of toggles the upper and lower ends of which are crossed and pivotally connected to said portions at spaced points, the centre pivots of the toggles being connected by nut and screw mechanism, means being provided to cause the crutch and base to move towards or away from each other in the vertical axis of the device during expanding or contracting movements. The said means may comprise pairs of drifting links connected to said centre pivots and associated with the base and crutch, and the appropriate ends of the drifting links may be connected to pins engaging slots in the base and crutch portions.

The connecting points on the crutch and base may be equally spaced on opposite sides of the vertical axis.

The nut and screw mechanism may comprise a block rotationally connected to one end of the screw, and a nut element, the block and nut being provided with trunnions by which they are pivoted to the toggles and drifting links.

In the accompanying drawings illustrating a jacking device according to the invention, Figure 1 is an elevation of the jack partly extended while Figure 2 is an end elevation corresponding thereto.

In carrying the invention into effect according to one convenient mode, a base 3 is provided having a shoe 4. The base member is connected by pairs of toggles to a crutch 5.

The toggles are duplicated on either side of the jack as will be seen from Fig. 2 and for convenience of description only those on one side will be referred to.

The toggle comprising the links 6 and 7 are pivotally connected at their outer ends to the crutch and base by pins 8 and 9 respectively while a second pair of links 6^a and 7^a are pivotally connected by the pins 8^a and 9^a. The pins 8 and 8^a are spaced apart and the links 6 and 6^a cross one another. Similarly the pins 9 and 9^a are

60 The joints of the toggles 6 and 7 are pivotally connected to the nut element 10 by the trunnion 11 while in a similar manner the links of the toggle 6^a and 7^a are pivotally connected to the block 12 by the trunnion 13.

65 The nut 10 is adapted to be engaged by the operating screw 14 having a boss 15 provided with a pin 16 by which it may be engaged by an operating handle of any suitable design, provided if desired with a universal joint.

70 The opposite end of the operating screw 14 is provided with a reduced plain part engaging an aperture in the block 12, a thrust ball bearing enclosed by the collar 17 being provided.

75 In order to steady the device and prevent tilting out of the vertical when in use, pairs of drifting links are provided. Thus one pair 18, 18^a is pivotally connected to the trunnion 11 while a second pair 19, 19^a is pivotally connected to the trunnion 13.

80 The free ends of these drifting links are connected together by the pins 20, 21 associated respectively with the crutch 5 and base 3. The pins 20, 21 pass through slots 22, 23, and are connected to the corresponding links on the other side of the jack. The slots are arranged in the vertical axis of the device and are slightly larger than the diameter of the pins.

85 In assembling the various links on each side of the jack they may be mounted in such order as to lie in planes adapted to facilitate the collapsing of the jack, and distance pieces or washers may be inserted where necessary.

90 The base 3 may be provided with a recess 24 to accommodate the screw 14 when the jack is collapsed and the shoe 4 may be curved at the ends as at 25 to facilitate its insertion under a vehicle.

95 The crutch 5 may be provided with 100 grooves 26 to accommodate the curved part of an axle or casing of a vehicle.

100 The crutch may be cast or formed of aluminum or other light material and having slotted steel plates 27 inserted in saw-cuts or grooves therein and riveted thereto for strengthening purposes, such plates extending downwardly a suitable distance according to the size of the slots 22.

105 Instead of fastening the plates by inserting them in the grooves and riveting, they may be positioned in the casting mould and

the aluminum or the like cast around them, so as securely to hold them in position, the plates, if necessary, being suitably shaped to form a good joint.

5 Alternatively, the whole of the crutch part may be formed in one casting of any suitable material.

According to another modification, the crutch and if desired the base may be 10 formed of stamped sheet metal, suitably bent into channel form.

We claim:—

1. A lifting jack comprising a base, a top, and a single threaded screw member disposed 15 therebetween and having a block at one end mounted for rotational movement and a nut engaging the screw thread, said block and

nut having a pair of laterally extending trunnions, pairs of crossed lifting bars pivoted on said trunnions and extending to the 20 top and base to which they are pivotally connected at pairs of spaced points, vertically extending guiding slots on the top and base, guide pins disposed in said slots and pairs of 25 guide links pivotally mounted at one end on said pins and at the other end on said trunnions.

2. A lifting jack as claimed in claim 1 wherein the lifting and guide bars extending respectively above and below the operating 30 screw are symmetrically arranged.
